UNITED STATES PATENT OFFICE.

WILLIAM L. MEEKER AND FRANCIS KEARNEY, OF NEWARK, NEW JERSEY.

IMPROVEMENT IN SWITCH-STANDS.

Specification forming part of Letters Patent No. 127,700, dated June 11, 1872.

Specification describing certain Improvements in Railroad Switches, invented by WILLIAM L. MEEKER and FRANCIS KEARNEY, of the city of Newark, in the county of Essex and State of New Jersey.

The invention relates to the manner of connection of the parts required for making the target and the rail move in the same direction.

In the accompanying drawing, A is the frame. B is the target. C is a segment of a gear-wheel on the end of the lever that holds the target by the socket z. D is a corresponding segment on the lever-bar, to the lower end of which is attached the connecting-rod y, having on its outer end the shoe x for the rail W. E is a bar, attached to both segments to obviate inconvenience from lost motion in the cogs,

and to keep the faces of the segments parallel with each other. The segments could be connected by two straps on plain smooth faces, the straps being, at their ends, the one secured to one segment and the other to the other segment. We prefer the gearing.

What we claim as our improvement is—

1. The segments C and D, as and for the purpose set forth.

2. The bar E, in combination with the segments C and D, as and for the purpose specified and shown.

WILLIAM LEWIS MEEKER.
FRANCIS KEARNEY.
